Primary Examiner—Jeffrey Asch
Attorney, Agent, or Firm—Thomas B. Tate[57] **CLAIM**

The ornamental design for a telephone keypad, as described and shown.

DESCRIPTION

The FIGURE is a top, front, and left side perspective view of a telephone keypad showing my new design, the rear and right side being mirror images of the front and left side respectively.

The broken line showing of a telephone set is for illustrative purposes only and forms no part of the claimed design.
